SHEET FED ROTARY PRINTING PRESSES

Hans J. Luehrs and Henry M. Clarke, Jr., Westerly, R. I., assignors, by mesne assignments, to The Cottrell Company, Westerly, R. I., a corporation of Delaware

Application February 27, 1953, Serial No. 339,302

21 Claims. (Cl. 101—183)

An object of this invention is to provide a sheet fed rotary printing press, in which a single and effective means is employed for conveying sheets, fed from a sheet supply pile, through one or more printing units, and one or more sheet drying units when used, to a sheet delivery pile, thereby ensuring perfect control of the sheets, by eliminating the usual plurality of sheet transfer devices for conveying the sheets to the sheet delivery pile.

Another object is to provide an endless chain carrier provided with grippers operable to take the sheets fed from the sheet supply pile and to convey them to a position where the sheets may be deposited directly from the endless chain carrier grippers onto the sheet delivery pile.

Another object is to provide a running sheet register, for registering the sheets before they are conveyed by the endless carrier grippers through the printing mechanism, to the sheet delivery pile.

Another object is to provide an automatic compensating means for the endless chain carrier, said means being preferably operable to independently compensate each of the side chains of the endless carrier, whereby the endless carrier grippers are maintained in their proper positions as they pass through the printing mechanism, and the drying mechanism if used.

Another object is to provide means whereby the sheets may be perfected without the necessity of being transferred from one carrier to another carrier, with the consequent loss of sheet register.

Another object is to provide sheet drying units comprising steam and water cylinders which may be rotated in either direction.

Another object is to provide novel gripper mechanism, in which the gripper bars are provided with off-set portions which are pivoted to opposite links of the carrier side chains in substantial alignment with the tips of the grippers, thereby maintaining the gripper tips in register with the path of the endless carrier chains.

Another object is to provide a gripper mechanism, in which the gripper bars are provided with off-set portions which are pivoted to two opposite links of the side chains.

Another object is to provide gripper bar registering means carried by the impression cylinders of the printing units, for ensuring the proper positioning of the gripper bars as the grippers pass around the impression cylinders.

Another object is to provide means whereby smaller head and tail spacing of the sheets may be used and smaller cylinders may be used to obtain increased production at lower surface speed.

Another object is to provide the impression cylinders of the printing units, and the cylinders of the drying units, when used, with peripheral recesses for receiving the gripper bars, as the grippers pass around the cylinders with the gripper tips at the peripheries of the cylinders.

Another object is to provide tracks for guiding the travel of the side chains and separate tracks for independently guiding the travel of the gripper supporting bars.

Practical embodiments of this invention are represented in the accompanying drawings, in which—

Figs. 1 and 1a are diagrams showing the endless chain carrier arranged to convey the sheets fed from the sheet supply pile, through first and second side multi-color printing units and their sheet drying units, to the sheet delivery pile;

Figs. 2 and 2a are similar diagrams, without the drying units;

Figs. 3 and 3a are diagrams showing the endless chain carrier arranged to convey the sheets, fed from the sheet supply pile, through a single multi-color printing unit and its sheet drying unit, to the sheet delivery pile;

Figs. 4 and 4a are similar diagrams, without the drying unit;

Figs. 5 and 5a are diagrams showing the endless chain carrier arranged to convey the sheets fed from the sheet supply pile, through a row, in the present instance two, of single color printing units and a sheet drying unit, to the sheet delivery pile;

Figs. 6 and 6a are similar diagrams, without the drying unit;

Fig. 7 is a detail cross-section of the automatic chain compensating means;

Fig. 8 is a detail longitudinal vertical section taken in the plane of the line VIII—VIII of Fig. 7 in a somewhat smaller scale;

Fig. 9 is a detail plan of one of the chain gripper bars located in a peripheral recess of an impression cylinder;

Fig. 10 is a longitudinal vertical section of the same;

Fig. 11 is a detail section showing one of the grippers in side elevation with the gripper bar located in a peripheral recess of a drying cylinder;

Fig. 12 is a detail section showing one of the front sheet register stops;

Fig. 13 is a detail side view of the grippers as they pass around one of the cylinders;

Fig. 14 is a front view of one of the gripper bar automatic positioning devices, and

Fig. 15 is a detail side view of one end of a gripper bar, its adjacent elements being shown in section.

In the several forms shown diagrammatically in Figs. 1, 1a to 6, 6a inclusive, the sheet supply pile is denoted by 1, the sheet delivery pile by 2, the endless chain carrier by 3, and its spaced sets of grippers by 4, and the initial manual chain take-up devices by 5. The running sheet register is denoted by 6 and the automatic chain compensating device, to be hereinafter described, by 7. The running sheet register 6 coacts with the endless chain carrier 3 to end and side register the sheets before the sheets are printed. This running sheet register 6 may be of any well-known or approved construction such, for instance, as that shown, described and claimed in any one of the co-pending applications of Hans J. Luehrs, filed April 4, 1951, Serial No. 219,198, now Patent No. 2,638,342; filed January 24, 1952, Serial No. 267,960, now Patent No. 2,638,343; and filed January 29, 1953, Serial No. 333,926; in which angularly disposed rollers serve as the means for advancing the sheets into front and side register with front and side register stops.

In the multi-color sheet perfecting rotary printing press shown in Figs. 1, 1a and 2, 2a, each of the two multi-color printing units of the printing mechanism is shown as comprising an impression cylinder 8, its peripheral gripper bar receiving recess 9; the two form cylinders 10; their peripheral gripper bar receiving recesses 11, and the inking mechanisms by 12. In Figs. 1, 1a, two sheet drying units are shown, each comprising a steam cylinder 13, a water cylinder 14, and their respective peripheral gripper bar receiving recesses 15 and 16.

In the non-perfecting rotary printing press shown in Figs. 3, 3a and 4, 4a, the single multi-color printing unit

is shown as comprising an impression cylinder 17, its peripheral gripper bar receiving recesses 18, the form cylinders 19, their peripheral gripper bar receiving recesses 20, and the inking mechanisms 21. In Figs. 3, 3a, a sheet drying unit is shown, comprising steam and water cylinders 22 and 23, and their respective peripheral gripper bar receiving recesses 24 and 25.

In the non-perfected rotary printing press shown in Figs. 5, 5a and 6, 6a, each of the single color printing units is shown as comprising an impression cylinder 26, its peripheral gripper bar receiving recess 27, the form cylinder 28, its peripheral gripper bar receiving recess 29, and the inking mechanism 30. In Fig. 5a, the drying unit is shown as comprising water and steam cylinders 31 and 32, and their peripheral gripper bar receiving recesses 33 and 34.

In the various forms illustrated, the side chains of the endless carrier 3 pass around sprockets 35 at the ends of the impression cylinders of the printing units and also around sprockets (not shown) at the opposite ends of the cylinders of the drying units when they are used. These side chains also pass around the necessary sprockets 36, shown in diagram, for passing the endless carrier through the desired endless path between the sheet supply and delivery piles 1 and 2. These side chains are also guided by upper and lower guide rails 37 and 38 located in the desired places.

The gripper assemblies each include, a gripper bar 39 which carries a row of grippers 4, the relatively stationary gripper jaws 40 being fixed along the said bar 39, and the relatively movable coating gripper jaws 41 being fast on a rock shaft 42 mounted in the stationary gripper jaws 40.

The gripper bar 39 is provided at each of its ends with an off-set portion, as a lateral arm 43, pivoted at 43* to one of two opposite links of the side chains, in substantial alignment with the tips of the gripper jaws 40, 41 so that the said tips will be maintained on the pitch line of the side chains 3 and the various cylinders and sprockets around which the side chains pass. Each gripper bar 39 is guided in its path by providing the ends of the gripper bar with rollers 44 which travel between upper and lower track rails 45 and 46. The rock shaft 42 of the movable gripper jaws 41 is provided at each end with an arm 47 carrying a roller 48, which is engaged by a stationary cam 49 to rock the shaft to open the grippers to take the registered sheets from the running sheet register 6. A stationary cam 49* is provided in position to engage said roller 48 to open the grippers for depositing the printed sheets onto the sheet delivery pile 2.

The gripper bar 39 may be provided with stops 39* for front registering the sheets as they pass through the running sheet register 6 into the grippers 4.

Automatic means arranged in pairs are provided along the endless chain carrier for independently compensating each of the side chains for taking up the slack therein. The compensating means of each pair is shown as including the following elements: A vertically movable guide rail section 38* of the lower guide rail 38 is mounted on two vertically disposed brackets 50 having upper and lower arms 51 and 52, the lateral ends of said arms being slidable on stationary vertical rods 53, fixed in the upper and lower supports 54 and 55 carried by the frame 56. Each bracket is shown as pressed upwardly by coil springs 57 extending along the rods 53 between the lower support 55 and the upper arm 51. The upper surfaces of these upwardly pressed guide rail sections 38*, over which the links of the side chains pass, are shown as convex. It will be noted that the portions of the upper guide rails 37 are omitted over the upwardly pressed lower guide rail sections 38* to permit the upward displacement of the side chains of the endless carrier. It will also be noted that the swinging gripper bar 39 will, because of its weight, travel along in a right

line between its upper and lower track rails 45 and 46 as the side chains are deflected by the independent upward movements of the lower guide rail sections 38*.

5 Gripper registering devices may be employed on the impression cylinders of the printing units for ensuring the proper positioning of the grippers as they pass the sheets around the impression cylinders, during the printing operations.

The device which I have shown for accomplishing the above result includes a spring pressed roller 58 on each end of the impression cylinder, which roller is carried by a support 59. These spring pressed rollers 58 engage the gripper bars 39 to press them against their upper track sections 45 while the grippers are located in the coating recesses in the plate and impression cylinders during the printing operation. It will also be noted that the pressure of these rollers 58 also causes the off-set portions 43 of the gripper bar 39 to exert pressure against the links of the side chains and thereby against 15 the flanks of the teeth of the sprocket 35, thereby accurately positioning the gripper bar assembly in the impression cylinder.

It is evident that various changes may be resorted to in the form, construction and arrangement of the several 20 parts without departing from the spirit and scope of this invention, and hence it is not intended to be limited to the particular embodiments shown and described herein.

What we claim is:

1. In a sheet fed rotary printing press, a printing unit, 30 including plate and impression cylinders, and an endless chain carrier including side chains, swinging gripper bars and rows of grippers carried thereby and operable to pass the sheets around the impression cylinder, said gripper bars being provided with off-set portions pivoted to opposite links of the side chains in substantial transverse alignment with the tips of the gripper jaws, whereby the said tips will be maintained in register with the path of the side chains.

2. In a sheet fed rotary printing press, a plurality of 40 printing units, each including plate and impression cylinders, and an endless chain carrier comprising side chains, swinging gripper bars and rows of grippers carried thereby and operable to pass the sheets around the impression cylinders, said gripper bars being provided with off-set portions pivoted to opposite links of the side chains in substantial transverse alignment with the tips of the gripper jaws, whereby the said tips will be maintained in register with the path of the side chains.

3. In a sheet fed rotary printing press, a printing unit, 50 including plate and impression cylinders, and an endless chain carrier including side chains, swinging gripper bars and rows of grippers carried thereby and operable to pass the sheets around the impression cylinder, said gripper bars being provided with off-set portions pivoted to opposite links of the side chains in substantial transverse alignment with the tips of the gripper jaws, whereby the said tips will be maintained in register with the path of the side chains.

55 4. In a sheet fed rotary printing press, a printing unit, including plate and impression cylinders, and an endless chain carrier including side chains, swinging gripper bars and rows of grippers carried thereby and operable to pass the sheets around the impression cylinder, said gripper bars being provided with off-set portions pivoted to opposite links of the side chains in substantial transverse alignment with the tips of the gripper jaws, whereby the said tips will be maintained in register with the path of the side chains, said impression cylinder having one or more peripheral recesses for receiving the gripper bars as the grippers pass around the cylinder, and means at both ends of said one or more recesses for exerting pressure on said gripper bars to maintain them in register therein.

60 5. In a sheet fed rotary printing press, a plurality of printing units, each including plate and impression cylinders, and an endless chain carrier including side chains, swinging gripper bars and rows of grippers carried thereby and operable to pass the sheets around the impression cylinders, said gripper bars being provided with offset portions pivoted to opposite links of the side chains in substantial transverse alignment with the tips of the gripper jaws, whereby the said tips will be maintained in register with the path of the side chains, said impression cylinders having one or more peripheral recesses 70 for receiving the gripper bars as the grippers pass around

the cylinders, and means at both ends of said one or more recesses for exerting pressure on said gripper bars to maintain them in register therein.

5. In a sheet fed rotary printing press, one or more printing units each including plate and impression cylinders, one or more drying units each including drying cylinders, and an endless chain carrier including side chains, swinging gripper bars and rows of grippers carried thereby, said gripper bars being provided with off-set portions pivoted to opposite links of the side chains in substantial traverse alignment with the tips of said rows of grippers, whereby the said tips will be maintained in register with the path of the side chains, said impression and drying cylinders each having one or more peripheral recesses for receiving the gripper bars as the grippers pass around the cylinders.

6. In a sheet fed rotary printing press, one or more printing units each including plate and impression cylinders, one or more drying units each including drying cylinders, and an endless chain carrier including side chains, swinging gripper bars and rows of grippers carried thereby, said gripper bars being provided with off-set portions pivoted to opposite links of the side chains in substantial transverse alignment with the tips of said rows of grippers, whereby the said tips will be maintained in register with the path of the side chains, said impression and drying cylinders each having one or more peripheral recesses for receiving the gripper bars as the grippers pass around the cylinders, and means at both ends of said impression cylinder recess or recesses for engaging said gripper bars to maintain them in register therein.

7. In a sheet fed rotary printing press, a printing unit including plate and impression cylinders, an endless chain carrier including side chains, swinging gripper bars and rows of grippers carried thereby, said gripper bars being provided with off-set portions pivoted to opposite links of the side chains in substantial transverse alignment with the tips of said rows of grippers, said plate and impression cylinders having coacting peripheral recesses for receiving the gripper bars as the grippers pass between said cylinders, and means for exerting pressure on said gripper bars to maintain the grippers in register as they pass between the plate and impression cylinders.

8. In a sheet fed rotary printing press, a printing unit including plate and impression cylinders, a drying unit including drying cylinders, and an endless chain carrier including side chains, swinging gripper bars and rows of grippers carried thereby, said gripper bars being provided with off-set portions pivoted to opposite links of the side chains in substantial transverse alignment with the tips of the said rows of grippers, said plate, impression and drying cylinders having peripheral recesses for receiving the gripper bars as the grippers pass between said plate and impression cylinders and around the said drying cylinders.

9. In a sheet fed rotary printing press, a printing unit including plate and impression cylinders, a drying unit including drying cylinders, and an endless chain carrier including side chains, swinging gripper bars and rows of grippers carried thereby, said gripper bars being provided with off-set portions pivoted to opposite links of the side chains in substantial transverse alignment with the tips of the said rows of grippers, said plate, impression and drying cylinders having peripheral recesses for receiving the gripper bars as the grippers pass between said plate and impression cylinders and around the said drying cylinders, and means for exerting pressure on said gripper bars to maintain the grippers in register as they pass between the plate and impression cylinders.

10. In a sheet fed rotary printing press, sheet supply and delivery piles, a printing unit, an endless chain carrier extending from the sheet supply pile to the sheet delivery pile and including side chains and gripper bars linked thereto to swing therefrom, which gripper bars

carry rows of grippers for conveying the sheets, fed from the sheet supply pile, through the printing unit to the sheet delivery pile.

11. A printing press according to claim 10 which includes devices spaced from the printing unit for automatically and independently taking up the slack in each of said side chains.

12. In a sheet fed rotary printing press, sheet supply and delivery piles, printing and drying units, an endless chain carrier extending from the sheet supply pile to the sheet delivery pile and including side chains and gripper bars linked thereto to swing therefrom, which gripper bars carry rows of grippers for conveying the sheets, fed from the sheet supply pile, through the printing and drying units to the sheet delivery pile.

13. A printing press according to claim 12 which includes devices spaced from the printing and drying units for automatically and independently taking up the slack in each of said side chains.

14. In a sheet fed rotary printing press, sheet supply and delivery piles, a printing unit, an endless chain carrier extending from the sheet supply pile to the sheet delivery pile and including side chains and gripper bars linked thereto to swing therefrom, grippers carried by said gripper bars, and a running sheet register located beneath the endless chain carrier and coacting therewith to register said sheets, said grippers being operable to take the registered sheets from the running sheet register and convey them through the printing unit.

15. A printing press according to claim 14 which also includes devices spaced from the printing unit for automatically and independently taking up the slack in each of said side chains.

16. In a sheet fed rotary printing press, sheet supply and delivery piles, a printing unit and at least one drying unit, an endless chain carrier extending from the sheet supply pile to the sheet delivery pile and including side chains and gripper bars linked thereto to swing therefrom, grippers carried by said gripper bars, and a running sheet register located beneath the endless chain carrier and coacting therewith to register said sheets, said grippers being operable to take the registered sheets from the running sheet register and convey them through the printing and drying units.

17. A printing press according to claim 16 which also includes devices spaced from the printing and drying units for automatically and independently taking up the slack in each of said side chains.

18. In a sheet fed printing press, sheet supply and delivery piles, a printing unit, an endless chain carrier including side chains and gripper bars linked thereto to swing therefrom, said gripper bars being provided with rows of grippers operable to convey the sheets from the sheet supply pile through the printing unit to the sheet delivery pile, fixed tracks for guiding the gripper bars, upper and lower guide rails for guiding the side chains to and from the printing unit and devices spaced from said printing unit operable to automatically and independently deflect each of the side chains to separately take up the slack therein.

19. In a sheet fed printing press, sheet supply and delivery piles; a printing unit, an endless chain carrier including side chains and gripper bars linked thereto to swing therefrom, said gripper bars being provided with rows of grippers operable to convey the sheets from the sheet supply pile through the printing unit to the sheet delivery pile, fixed tracks for guiding the gripper bars, upper and lower guide rails for guiding the side chains to and from the printing unit and devices spaced from said printing unit operable to automatically and independently deflect each of the side chains to separately take up the slack therein, said devices including spring pressed guide rail sections.

20. In a sheet fed printing press, sheet supply and delivery piles, printing and drying units, an endless chain

carrier including side chains and gripper bars linked thereto to swing therefrom, said gripper bars being provided with rows of grippers operable to convey the sheets from the sheet supply pile through the printing and drying units to the sheet delivery pile, fixed tracks for guiding the gripper bars, upper and lower guide rails for guiding the side chains to and from the printing and drying units and devices spaced from said printing and drying units operable to automatically and independently deflect each of the side chains to separately take up the slack therein.

21. In a sheet fed printing press, sheet supply and delivery piles, printing and drying units, an endless chain carrier including side chains and gripper bars linked thereto to swing therefrom, said gripper bars being provided with rows of grippers operable to convey the sheets from the sheet supply pile through the printing and drying units to the sheet delivery pile, fixed tracks for guiding the gripper bars, upper and lower guide rails for guiding

the side chains to and from the printing and drying units and devices spaced from said printing and drying units operable to automatically and independently deflect each of the side chains to separately take up the slack therein, 5 said devices including spring pressed guide rail sections.
